UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

JARRING MECHANISM FOR SCREENING OR SEPARATING MACHINES.

1,229,820.

Specification of Letters Patent. Patented June 12, 1917.

Application filed January 10, 1917. Serial No. 141,588.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Jarring Mechanisms for Screening or Separating Machines, of which the following is a specification, reference being had therein to the accompanying drawing.

This invention relates to that class of inclined screening or separating machines in which the screen are percussively jarred or vibrated, and the invention relates more particularly to certain improvements in the machine of the Bell and Sturtevant Patent No. 923,108, dated May 25, 1909, in which the screens are jarred from hammers or 20 strikers arranged below the screens. The present improvement has special reference to the hammer or vibrating mechanism for percussively jarring the fine screens of the separators.

25 In accordance with the present invention the fine screen is percussively jarred from below by means of hinged hammers striking at intervals on the bottoms of spring-sustained impact bars which yieldingly support the screen or screens to be jarred.

The accompanying drawing is a detail view illustrating one of the improved jarring devices, a plurality of which will of course be used in each separating machine 30 for jarring the screen or screens.

Referring to the drawing, 12 denotes the bottom of the screen box or casing to which is attached a hanger 13 a plurality of which will be provided for supporting a rotating 40 shaft 14 provided with disks 15 to which are hinged hammers 16. Attached to the casing parts 12 is a support 17 through which extends an impact bar or pin 18 encircled by a supporting spring 19 which 45 thus yieldingly sustains said impact bar in said support. The impact bar is provided at its top with a head 18a between which and the bottom of said support said spring 19 is

interposed, and on which head rests a transverse protection plate 20 attached to a wire 50 mesh screen 21, so that the said screen will be yieldingly supported by the impact bars 18, a plurality of which will, in practice, be provided.

From the foregoing it will be understood 55 that when the machine is in operation the screen 21, which is yieldingly supported by the impact bars 18, will be percussively jarred by means of repeated blows of the hinged revolving hammers 16 acting up- 60 wardly on the said impact bars.

Having thus described my invention I claim and desire to secure by Letters Patent:

1. In a separator, the combination with a 65 screen, of impact bars by which said screen is supported and rotating hammers acting intermittently from below on said impact bars.

2. In a separator, the combination with a 70 screen, of yieldingly-mounted impact bars by which said screen is elastically supported and rotating hammers acting intermittently from below on said impact bars.

3. In a separator, the combination with a 75 screen casing part provided with supports, of impact bars passing through said supports and provided with heads, springs interposed between said heads and the bottoms of said supports, a screen elastically supported by the said spring-mounted impact bars, and hammers acting at intervals on said impact bars.

4. In a separator, the combination with a screen casing part provided with supports, of impact bars passing through said supports and provided with heads, springs interposed between said heads and the bottoms of said supports, a screen elastically supported by the said spring-mounted impact bars, hammers acting at intervals on said impact bars, and revolving disks to which said hammers are hinged or pivoted.

In testimony whereof I affix my signature.

THOMAS JOSEPH STURTEVANT.
